VEHICLE MIRROR SUPPORT

Floyd E. Wallace and Percy E. Elwell, El Segundo, Calif.,
assignors to Detroit Automotive Products Company, doing business as Detroit Products Company, El Segundo, Calif., a corporation of California

Filed Sept. 12, 1967, Ser. No. 8,566

Term of patent 14 years

Int. Cl. D12—14

U.S. Cl. D14—6

FIG. 1 is a rear elevational view of a vehicle mirror support showing our new design;

FIG. 2 is a side elevational view showing the mirror support;

FIG. 3 is a top plan view thereof.

The mirror and vehicle, shown in broken lines, are included only for illustrative purposes.

We claim:

The ornamental design for a vehicle mirror support, as shown and described.
